US00D557876S

(12) United States Design Patent (10) Patent No.: US D557,876 S
Lenell (45) Date of Patent: * Dec. 25, 2007

(54) CONFECTIONERY PRODUCT

(75) Inventor: Peter Lenell, Stockholm (SE)

(73) Assignee: Tinus Företagstjänst AB, Haninge (SE)

() Term: 14 Years

(21) Appl. No.: 29/275,063

(22) Filed: Dec. 12, 2006

(30) Foreign Application Priority Data

Jun. 13, 2006 (SE) 2006/0364

(51) LOC (8) Cl. 01-01

(52) U.S. Cl. D1/101

(58) Field of Classification Search D1/100-2, D1/105-6, 116, 118, 120-30; 426/94, 138, 426/143, 279, 281-4, 391, 514, 275, 277, 426/292, 295, 572, 566, 660, 496
